CONTROL VALVE FOR GRAIN DIVIDERS

Filed April 13, 1950

UNITED STATES PATENT OFFICE

2,605,076

CONTROL VALVE FOR GRAIN DIVIDERS

Willard H. Tanke, La Crosse, Wis., assignor to
Allis-Chalmers Manufacturing Company, Milwaukee, Wis.

Application April 13, 1950, Serial No. 155,610.

5 Claims.

(Cl. 251—13)

1

This invention relates generally to grain sacking devices and is more particularly concerned with an improvement of the type of sacking device having a grain chute with diverging leg portions and a valve for selectively directing the grain into one or the other of the leg portions.

In the bagging of grain, particularly after it has been milled for feed or the like, the loss of grain through leakage is often considerable, and therefore, it is desirable to avoid such waste wherever possible. One common form of bagging attachment comprises a single chute through which the grain passes into a selected one of two diverging leg portions of the chute and then into a bag held open at the end of the leg. When a bag has been filled, the entrance into that leg portion may be blocked by a valve means, and the grain is then diverted into a bag held by the other leg portion of the chute so that the filled bag may be removed and replaced by an empty one. Many types of valve means have been employed to thus divert the flow of grain from one leg to the other but leakage past the valve into the bagless leg has remained a constant problem. And it seems that the area immediately surrounding the axis of the valve movement is the scene of the greatest loss in that it has been difficult to provide an effective seal at the junction of the two leg portions and the valve without hampering the movement of the valve.

It is, therefore, the primary object of this invention to provide a valve means, for the above mentioned type of grain divider, having a flexible sealing means coactable therewith to effectively and positively prevent flow from one side of the valve to the other in the region of the axis of movement of the valve.

Another object of the present invention is to provide a valve means, for a grain divider having a pair of diverging legs separated by an angular crotch and which valve means is swung about an axis adjacent and parallel to said crotch, with a flexible sealing means to prevent flow from one side of the valve to the other in the region of the crotch and wherein the spacing of the valve axis from the crotch is consequently not critical and does not cause a leakage of grain therebetween.

It is also an object of this invention to provide a valve and sealing means therefor, affording the advantages mentioned above, which is simple and relatively inexpensive to construct and which does not require frequent repair or replacement.

The construction and operation of apparatus

2

embodiment this invention will become more readily apparent as the disclosure progresses and particularly points out additional objects and advantages of special importance. And, accordingly, the present invention may be considered as comprising the various constructions, combinations and/or subcombinations of parts as herein-after more fully set forth in the detailed description and appended claims, reference being had to the accompanying drawings, in which:

Fig. 1 is a side elevation of apparatus embodying the present invention with portions broken away for sake of clarity;

Fig. 2 is a view taken along line II—II in Fig. 1; and

Fig. 3 is a view taken along line III—III in Fig. 1.

Referring to Fig. 1 it may be seen that apparatus embodying the present invention comprises generally a grain divider 1 having an upper main chute 2 terminating at its lower end in a pair of diverging leg portions 3 and 4, and a manually operable valve means 6 selectively positionable to direct grain into one or the other of the leg portions. More specifically, grain divider 1 is preferably made of sheet metal or the like with a flanged portion 7 formed at the upper end thereof for attachment of the grain divider to a mill chute 8, as by rivets 10. The lower portion of the divider or bagging attachment comprises a pair of diverging sheet metal leg portions 3 and 4 having adjacent spaced edges joined by a dihedral angular crotch member 11 extending the width of the legs (Fig. 2). Opposite end portions of crotch member 11 are provided with similar flanges 12 affording surface bearing contact with adjacent edges of sheet metal leg portions 3 and 4 and these contacting surfaces are fixedly secured together as by welding.

The lower end of crotch member 11 is bent at an acute angle with respect to the main surface thereof to form a hook-like trough 13 for holding an edge portion of a bag 15 in place with respect to the grain divider. And, in this connection, it will be noted that the outwardly facing surfaces of leg portions 3 and 4, opposite crotch member 11, each mount a bag holding device 16 which is coactable with trough 13 to removably secure a bag in position at the lower end of each leg. Device 16 comprises generally a bracket structure 17 fixed, as by rivets 18, to the leg portion of the grain divider and having a serrated or notched lower surface 20. A manually operable lever 21 is pivotally attached to the upper portion of bracket 17 for movement

with respect to serrated surface 20 so as to releasably grip the edge portion of a bag therebetween, as shown in Fig. 1. The grain divider structure just described should suffice for a complete understanding of the present invention, and it is, therefore, believed that a more detailed description of such structure is unnecessary.

Looking also at Figs. 2 and 3 it is noted that control valve means 6 is provided for the purpose of selectively diverting the flow of grain, or other material being dispensed through mill chute 8, into either of the two leg portions 3 and 4 and thence into bags held by device 16. Valve means 6 comprises generally an operating crank 19 having a shaft portion 22 which extends through and is journaled in opposite walls of divider 1 in vertically spaced relation to the apex of crotch member 11 for rotation about an axis parallel thereto, and a pair of spaced plate members 23 flanking shaft 22 on opposite sides thereof. These plates diverge downwardly and present inner edges 24 which are spaced from the top surface of crotch member 11 and are generally coextensive therewith. The opposite side edges of plates 23, that is the edges adjacent the opposite ends of shaft 22, extend to the opposed side wall portions of divider 1, as best seen in Fig. 2. Plate members 23 are somewhat semi-elliptical in shape to conform with the preferred configuration of the internal surface of the grain divider and a series of bolts 25 are disposed in tangential relation to shaft 22 through pairs of aligned openings (not shown) in the plates to secure same in place with respect to crank 19. As shown in Fig. 3, the preferred arrangement for bolts 25 includes a bolt in tangential contact with the under side of the bent center portion of shaft 22 and at least one bolt adjacent each end of shaft 22 in tangential contact with respect to the upper side thereof.

The outer end portion 26 of plates 23, that is, the portions most remote from shaft 22 are joined, as by spot welding, to form a unitary valve structure rotatable about the axis afforded by shaft 22.

As previously mentioned, the inner end portions 24 of plate members 23 are flared somewhat and extend to a position in proximate relation to crotch member 11. And a flexible sealing means 27, which may be made of rubber or the like, is fixedly secured to the apex portion of crotch member 11 and presents a free end portion 28 extending upward into the space between valve end portions 24. More specifically, a pair of similar longitudinal strips of flexible material are joined along one edge thereof to form a bifurcated structure which is placed on crotch member 11 with the free edges thereof secured to opposite sides of member 11 and the joined edges extending upward between valve end portions 24. Flexible sealing means 27 may be fixedly secured to the crotch member in any suitable manner, but it is preferred that such means be removably inserted in place since it is wearable and, consequently, subject to replacement. And for this reason there are provided clamping elements 30 which are detachably secured to crotch member 11 by bolts 31 affording means for clamping the free edges of sealing means 27 in place. Thus it is seen that the leg portions 3 and 4 of the grain divider are sealed with respect to each other at their line of juncture through the coaction of valve 6 and sealing means 27. And since the remainder of the valve means conforms with the internal configuration of a leg

portion of the grain divider, it is selectively movable to effectively block off either leg with respect to the main chute 2 and thus divert the flow of grain to the other leg.

5 And although shown with respect to a particular embodiment, it is not intended to thereby limit the present invention to the construction shown and described as various modifications thereof within the scope of the appended claims may occur to persons skilled in the art.

It is claimed and desired to secure by Letters Patent:

1. In a grain divider having a main chute with a pair of diverging legs separated by a dihedral angular crotch, a valve operating shaft journaled in the side walls of said chute for rotation about an axis spaced from and generally parallel to the apex of said crotch, a valve member attached to said shaft for oscillation between two limiting positions in which it substantially blocks one and the other of said legs from communication with said main chute, said valve having spaced plate portions flanking said shaft on opposite sides and extending in the general direction of said crotch, and a flexible resilient sealing strip carried by said crotch and having a free edge extending upward between said plate extensions, said strip being engaged by opposite ends of said plates with said valve in its limiting positions.

2. In a grain divider having a main chute with a pair of diverging legs separated by a dihedral angular crotch, a valve operating shaft journaled in the side walls of said chute for rotation about an axis spaced from and parallel to the apex of said crotch, a valve member attached to said shaft for oscillation between two limiting positions in which it substantially blocks one and the other of said legs from communication with said main chute, said valve having spaced plate portions flanking said shaft on opposite sides and extending in the general direction of said crotch, and a flexible sealing means comprising a pair of resilient members secured to adjacent side walls of said legs and presenting a free edge extending upward from said crotch and between said plate extensions, said resilient members being engaged by opposite ends of said plates with said valve in its limiting position.

3. In a grain divider having a main chute with a pair of diverging legs separated by a dihedral angular crotch, a valve operating shaft journaled in the side walls of said chute for rotation about an axis spaced from and parallel to the apex of said crotch, a valve member attached to said shaft for oscillation between two limiting positions in which it substantially blocks one and the other of said legs from communication with said main chute, said valve having spaced plate portions flanking said shaft on opposite sides and extending in the general direction of said crotch, and a flexible sealing means comprising a pair of resilient members secured to the adjacent side walls of said legs and presenting free edge portions which are joined together and extend upward between said plate extensions, said resilient members being engaged by opposite ones of said plates with said valve in its limiting position.

4. In a grain divider having a main chute with a pair of diverging legs separated by an angular crotch, a valve operating shaft journaled in the side walls of said chute for rotation about an axis spaced from and parallel to the apex of said crotch, said shaft being formed of a single length of rod material bent intermediate its journaled

portions to form a crank, a valve member attached to said shaft for oscillation between two limiting positions in which it substantially blocks one and the other of said legs from communication with said chute, said valve having spaced plate portions flanking said shaft on opposite sides and extending in the general direction of said crotch, and a flexible sealing strip carried by said crotch and having a free edge extending upward between said plate extensions, said strip being engaged by opposite ones of said plates with said valve in its limiting positions.

5. In a grain divider having a main chute with a pair of diverging legs separated by an angular crotch, a valve operating shaft journaled in the side walls of said chute for rotation about an axis spaced from and parallel to the apex of said crotch, said shaft being formed of a single length of rod material bent intermediate its journaled portions to form a crank, a valve member attached to said shaft for oscillation between two limiting positions in which it substantially blocks one and the other of said legs

from communication with said chute, said valve having spaced plate portions extending in the general direction of said crotch and clamped in flanking relation to said shaft by a series of parallel bolts spaced axially therealong with one of said bolts being in tangential contact with said shaft within said crank bend, and a flexible sealing strip carried by said crotch and having a free edge extending upward between said plate extensions, said strip being engaged by opposite ones of said plates with said valve in its limiting positions.
